UNITED STATES PATENT OFFICE

2,603,960

LIQUID FUEL BURNER

Cornelius George Nobbs, London, England

Application November 13, 1948; Serial No. 59,898
In Great Britain November 17, 1947

5 Claims. (Cl. 67—68)

1

The present invention relates to a liquid fuel burner of the kind comprising a plurality of wicks, each mounted in a tube secured at its lower end to a circular plate and at its upper end sliding within a sleeve member, the latter being provided with orifices, each of which serves for the passage of the upper end of a wick, and means being provided for raising or lowering all the wicks simultaneously.

The object of this invention is the provision of means whereby all the wicks can be ignited simultaneously.

For this purpose the circular row of wicks is surrounded by a circular strip of absorbent material that makes contact with and absorbs fuel from each of the wicks. If one of the wicks is ignited, the fuel in the absorbent strip is also ignited, thus producing a short-lived circular flame that causes almost simultaneously ignition of all the wicks. The short life of this circular flame is due to the fact that the flame flash on first lighting the wicks exhausts the oil in the absorbent material so that the flame dies out rapidly. The absorbent material is in point contact only with the wicks, and when the latter are alight there is insufficient contact with them to feed the absorbent material continuously to maintain a flame.

According to a further feature of this invention means are provided whereby "char" or corrosion from the upper ends of the wicks can be removed from all the wicks simultaneously.

To achieve this result a scraping or cutting ring concentric with the circular absorbent strip is fitted within the upper part of the burner, the strip participating in the movements of the ring. The inner edge of this ring, to which a rotary movement can be applied, is provided with a cutting edge, and also with spaced arcuate recesses which partially surround the tops of the wicks. If an angular movement of small amplitude is applied to this ring, which is preferably of metal, the charred or corroded tops of the wicks will be simultaneously severed.

According to another feature of this invention there is provided a device for clamping the wicks in the tubes previously mentioned. This device is in the form of a strip or thread of some readily destructible material, which is indented at spaced intervals, and wound spirally around the exterior of the wick. The destructible thread is melted or consumed by the flame of the wick, but remains intact and operative along the unburnt portion of the wick. When it is desired to raise a wick, tension is manually applied to the latter

which is thus slightly stretched, thus decreasing the diameter of the indented coil, freeing the indentations from contact with the wall of the tube, and allowing of an upward movement of a wick. If on the other hand a wick is to be clamped in position, the wick is compressed, thus increasing the diameter of the spiral which in consequence closely engage the wall of the tube.

The tubes are conveniently indented to cooperate with the spirally wound thread upstanding from the wick. The purpose of this is to facilitate the introduction of a wick into its tube, and also the withdrawal of a worn wick.

One form of construction of the invention is illustrated in the annexed drawings, in which:

Fig. 1 is a plan of the burner,

Fig. 2 is a section on the line 2—2 of Fig. 1,

Fig. 3 is an enlarged detail view of a wick and wick tube,

Fig. 4 is a detail view of a wick-clamping device, and

Fig. 5 is an enlarged section showing the device for igniting the wicks.

Referring first to Figs. 1 and 2, *a* is a lower circular platform which is vertically movable and to which are secured a number of equidistantly spaced tubes *b*, each housing a wick *c* and being surrounded at its upper part by a sleeve *d*. The latter are secured at their lower ends to an upper fixed platform *e* provided with a depending flange *f* and secured to the burner oil reservoir. At their upper ends the sleeves are secured to a fixed annular trough *g*. An intermediate platform *h* is located between the platforms *a* and *e*, this platform being traversed by vertical pillars *i* partly housed in sleeves *k* secured to the platform *e*, and being vertically movable by means of a rack *l* secured to the platform *h* and a pinion *m* mounted on a horizontal shaft *n* and thumb-piece *o*, the pinion *m* rotating in a housing upstanding from the platform *e*.

The annular trough *g* is provided with circular holes *p* for the passage of the wicks, and the wick tubes can be raised and lowered relatively to the annular trough by means of a vertical rack *q* secured at its lower end to the platform *a* and a pinion *r* operated by a shaft *s* and thumb piece *t*. The parts so far described are of known construction.

According to this invention circular strip *u* of absorbent material surrounds the wicks, and makes contact with an absorbent oil from each of them. With this arrangement, if one of the wicks is ignited by hand, the remaining wicks are rapidly ignited by the strip *u* which provides a

short-lived flame. The strip u is concentric with a scraping or cutting ring v which is manually rotatable through the medium of slots w in the cutting ring v and collars x on top of the pillars j . This ring v is L-shaped in section and is provided on its horizontal part with inner edges v' and spaced arcuate recesses v^2 that surround the tops of the wicks, the portions v' serving, if a small angular movement is imparted to the ring v , to remove the charred or corroded tops of the wicks. The slots w in the ring v are held by the collars x on top of the pillars j as shown in Figure 5. The ring v is adjusted in height by means of the intermediate platform h operated by the rack l , pinion m , shaft n and thumb piece o .

According to a further feature of this invention means are provided for clamping the wicks c in their tubes b . Each clamping device is in the form of a strip or thread y of some readily destructible material such as nylon, which is corrugated or indented at intervals as shown in Figure 4, and which is wound spirally around a wick as shown in Figs. 2 and 3. When it is desired to raise a wide tension is applied to the latter which is thus slightly stretched, thus decreasing the radius of the spiral, freeing the indentations from contact with the walls of the wick tubes, and allowing of upward movement of the wicks. If on the other hand a wick is to be clamped in position, such wick is compressed thus increasing the radius of the spiral which in consequence closely engages the wall of the tube.

In order to facilitate the introduction of a wick into or its withdrawal from a tube, the latter is internally indented at z , as shown in Figs. 2 and 3 to cooperate with a spirally wound thread upstanding from the wick.

I claim:

1. A liquid fuel burner comprising a plurality of tubes each housing a wick, a platform on which the tubes are mounted at their lower ends in an annular row, a plurality of sleeve members in each of which is slidable the upper end of one of the said tubes, an annular trough secured upon the upper ends of the sleeve members, the latter opening into the base of the trough to admit thereto the tops of the wicks, means for raising and lowering the platform to raise and lower the tops of the wicks in the annular trough, an annular strip of absorbent material within the annular trough and in point contact with the tops of the wicks for absorbing fuel therefrom, and a cutting ring mounted for rotation within the trough and having cutting edges laterally adjacent to the tops of the wicks for cutting the latter upon rotation of the cutting ring.

2. A liquid fuel burner comprising a plurality of tubes each housing a wick, a platform on

which the tubes are mounted at their lower ends in an annular row, a plurality of sleeve members in each of which is slidable the upper end of one of the said tubes, an annular trough secured upon the upper ends of the sleeve members, the latter opening into the base of the trough to admit thereto the tops of the wicks, means for raising and lowering the platform to raise and lower the tops of the wicks in the annular trough, and an annular strip of absorbent material within the annular trough and in point contact with the tops of the wicks for absorbing fuel therefrom.

3. A liquid fuel burner as claimed in claim 2 wherein means are provided for securing the wicks in the tubes, which means comprises a thread of destructible material which is indented and wound spirally round the exterior of a wick.

4. A liquid fuel burner as claimed in claim 2, wherein each wick tube is indented to cooperate with a spirally wound thread upstanding from the wick.

5. A liquid fuel burner comprising a plurality of wicks, tubes for housing said wicks, a platform on which the tubes are mounted at their lower ends in an annular row, means for supporting said platform, a plurality of members in each of which is slidable the upper end of one of said tubes, means for supporting said members, an annular trough secured upon the upper ends of said members, said members opening into the base of the trough to admit thereto the tops of the wicks, and a cutting ring mounted for rotation within the trough and having cutting edges laterally adjacent to the tops of the wicks for cutting the wicks upon rotation of the cutting ring.

CORNELIUS GEORGE NOBBS.
